CLAIM

The ornamental design for a linear slide extrusion, as shown and described.

DESCRIPTION

FIG. 1 is a right side/front/top isometric view of my new design, the view being broken to indicate that the design may be of any length;

FIG. 2 is an end elevational view thereof;

FIG. 3 is a side elevational view thereof, the opposite side being identical to that shown, and the view being broken to indicate that the design may be of any length;

FIG. 4 is a top plan view thereof, the view being broken to indicate that the design may be of any length; and,

FIG. 5 is a bottom plan view thereof, the view being broken to indicate that the design may be of any length.
